FOLDING BED REST

Filed June 3, 1949

UNITED STATES PATENT OFFICE

2,529,350

FOLDING BED REST

Robert M. Posz, Glendale, Calif.

Application June 3, 1949, Serial No. 96,914

11 Claims. (Cl. 5—327)

1

My invention relates to folding bed rests and included in the objects of my invention are:

First, to provide a bed rest which attaches to a side frame of a bed, such as a hospital bed, and extends over the mattress so that a patient may sit upright facing crosswise to the bed, the bed rest incorporating side arms and a back rest so that weakened patients may practice a seated posture with a minimum of discomfort and with a feeling of security.

Second, to provide a bed rest which folds into a flat package for storage and which may be readily and quickly secured to or removed from a bed with minimum effort on the part of a nurse or attendant.

Third, to provide a bed rest which is readily adaptable to various styles of bed structures.

With the above and other objects in view, as may appear hereinafter, reference is directed to the accompanying drawings, in which:

Figure 1 is a perspective view of my folding bed rest shown in position on a bed, the bed being shown fragmentarily.

Figure 2 is an enlarged fragmentary sectional view through 2—2 of Figure 1, showing the manner in which the back frame joins to the side frames of the device.

Figure 3 is a top view of my bed rest in its folded position for storage.

Figure 4 is a further enlarged fragmentary sectional view through 4—4 of Figure 1 illustrating the hinged connection between the back frame and one of the side frames.

Figure 5 is a fragmentary sectional view through 5—5 of Figure 1 showing one form of attaching means for my device.

Figure 6 is a fragmentary view similar to Figure 5 showing a modified form of attaching means.

Figure 7 is another fragmentary sectional view showing a further modified form of attaching means.

My folding bed rest includes a pair of side frames 1 formed of metal tubing and bent in the form of rectangular loops. Three of the corners of each loop are rounded. However, at the fourth or forward lower corner the vertical portion of the frame projects downwardly to form a leg 2. Each vertical leg receives a telescoping extension tube 3 having a series of perforations 4 adapted to receive a pin 5 secured to the vertical leg 2 by a leaf spring 6.

As shown best in Figure 5, the lower end of each extension tube is connected to a clamping foot 7 by means of a pivotal connection 8 allowing

2

limited pivotal movement. The clamping foot includes a hooked end 9 which is adapted to fit over the horizontal flange A of an angle iron B, constituting a part of the bed frame. In hospital beds two such angle members, mounted one above the other, are available for attachment of the clamping foot.

The forward portion of the foot opposite from the hooked end 9 is provided with a depending boss 10 which is threaded to receive a thumbscrew 11 adapted to cooperate with the hooked end 9 to clamp the angle member B. It is preferred that the slot formed by the hooked end 9 be normally disposed at a slight angle as indicated by the axis line C (shown exaggerated in Figure 5) so that on tightening, a biasing strain is placed on the flange A and hooked end. This arrangement insures a tight fit which does not work loose.

20 A modified form of foot member designated 12 is shown in Figure 6. In this case the foot member is U-shaped, one leg of which is joined by a pivotal connection 13 to the extension tube 3. The other leg of the U-shaped foot member extends behind the vertical flange D of an angle member. The first of the pivoted legs receives a thumbscrew 14 to engage and clamp the vertical flange D.

25 A further modified foot designated 15 is shown in Figure 7. In this construction the foot itself is similar in form to the foot member 7, the essential difference being that it is designed to engage the vertical flange D of an angle iron. For this purpose a vertically directed bracket 16 is provided, which is joined by a pivotal connection 17 to the extension tube 3. The modified foot 15 is provided with a hooked portion 18 at its lower end, which fits under the flange D. A laterally directed boss 19 overlies the angle iron and receives a thumbscrew 20.

30 A back frame 21 is provided. The back frame is formed of tubing bent to define a rectangular loop with rounded corners. The lower bar 22 of the back frame is bent so as to be offset backwardly from the vertical and top bars of the frame. This places the lower bar 22 clear of the patient's buttocks and also facilitates compact folding of the side frames 1. The vertical and top bars of the frame receive a fabric cover 23 in the form of a slipcover closed at its top and two sides. The upper corners of the cover 23 are notched as indicated by 24 to expose the upper corners of the back frame. The lower margin of the cover 23 terminates above the lower bar 22. Immediately below the cover the side bars of

the back frame are provided with clamp brackets 25. Each clamp bracket comprises a pair of clamp elements having complementary parallel channels which respectively fit the vertical bars of the back frame and the rear vertical portions of the side frames 2. The clamp brackets 25 are provided with pins 26 which penetrate the side bars of the back frame to prevent pivotal movement. The side frames, however, pivot in the clamp brackets 25. Setscrews 27 join the two halves of each clamp bracket.

The vertical side bars of the back frame 21 may be bent slightly above the clamp brackets 25 so that the back frame may occupy an inclined position. A retainer strap 28 is attached to the mid-portion of the lower bar 22 and is adapted to extend across the bed for attachment to the bed frame opposite from the angle member B.

My folding bed rest is employed as follows:

When stored the side frames 1 fold in overlapping relation as shown in Figure 3 so that the device may be stored in a minimum amount of space. To place the device on the bed the side frames are opened in parallel relation, the extension tubes adjusted to appropriate length and the clamping feet 7, 12 and 15, as the case may be, are secured to the side frame of the bed. The strap 28 is drawn tight and secured to the opposite side frame of the bed. If it is inconvenient to remove the patient from the bed while placing the device in position, the patient may be seated at one side of the bed and the device brought into position from the opposite side of the bed by extending the side frames along either side of the patient. The clamping feet are then fastened and the retainer strap secured.

Having fully described my invention, it is to be understood that I do not wish to be limited to the details herein set forth, but my invention is of the full scope of the appended claims.

I claim:

1. A device for installation on a bed to support a patient in a seated position, involving: a tubular back frame of rectangular form; a pair of tubular side frames also of rectangular form pivotally connected to said back frame; vertical leg members projecting from said side frames; and clamp means for securing said vertical legs to the side rail of a bed frame to dispose said side frames vertically upon a bed with said back frame upright between said side frames.

2. A device for installation on a bed to support a patient in a seated position, involving: a tubular back frame of rectangular form; a pair of tubular side frames also of rectangular form pivotally connected to said back frame; a vertical leg member continuing from one margin of each side frame to overhang a side of a bed; extension members for said leg members; and clamping devices pivotally attached to said extension members constructed and arranged to be secured to the side rail of said bed.

3. A device for installation on a bed to support a patient in a seated position, involving: a pair of tubular side frames of "P" form to provide legs adapted to project over the side of a bed for attachment to the frame of the bed and to dispose the loop portions of said frames in upright position over the bed; a tubular back frame of rectangular form secured to the rear ends of said side members remote from said legs, the lower bar of said back frame being arched rearwardly with respect to said side frames; and a yieldable covering for said back frame.

4. A device for installation on a bed to support

a patient in a seated position, involving: a tubular back frame of rectangular form; a pair of tubular side frames also of rectangular form pivotally connected to said back frame; vertical leg members projecting from said side frames; clamp means for securing said vertical legs to the side rail of a bed frame to dispose said side frames vertically upon a bed with said back frame upright between said side frames; and a tension strap connected to the lower bar of said back frame for attachment to the opposite side of said bed from legs.

5. A device for installation on a bed to support a patient in a seated position, involving: a pair of tubular side frames of "P" form to provide legs adapted to project over the side of a bed for attachment to the frame of the bed and to dispose the loop portions of said frames in upright position over the bed; a tubular back frame of rectangular form secured to the rear ends of said side members remote from said legs, the lower bar of said back frame being arched rearwardly with respect to said side frames; a yieldable covering for said back frame; and a tension strap connected to the lower bar of said back frame for attachment to the opposite side of said bed from legs.

6. A device for installation on a bed to support a patient in a seated position, involving: a pair of tubular side frames of "P" form to provide legs adapted to project over the side of a bed; extension members for said leg members; clamping devices pivotally attached to said extension members constructed and arranged to be secured to the side rail of said bed; and a back frame connected to and between said side frames.

7. A device for installation on a bed to support a patient in a seated position, involving: a pair of tubular side frames of "P" form to provide legs adapted to project over the side of a bed; extension members for said leg members; clamping devices pivotally attached to said extension members constructed and arranged to be secured to the side rail of said bed; a tubular back frame of rectangular form secured to the rear ends of said side members remote from said legs, the lower bar of said back frame being arched rearwardly with respect to said side frames; and a yieldable covering for said back frame.

8. A device for installation on a bed to support a patient in a seated position, involving: a pair of tubular side frames of "P" form to provide legs adapted to project over the side of a bed; extension members for said leg members; clamping devices pivotally attached to said extension members constructed and arranged to be secured to the side rail of said bed; a tubular back frame of rectangular form secured to the rear ends of said side members remote from said legs, the lower bar of said back frame being arched rearwardly with respect to said side frames; a yieldable covering for said back frame; and a tension strap connected to the lower bar of said back frame for attachment to the opposite side of said bed from legs.

9. A device for installation on a bed to support a patient in a seated position, involving: a tubular back frame of rectangular form; a pair of tubular side frames also of rectangular form pivotally connected to said back frame; vertical leg members projecting from said side frames; and means for securing said vertical legs to the side rail of a bed frame to dispose said side frames vertically upon a bed with said back frame upright between said side frames.

10. A device for installation on a bed to support a patient in a seated position, involving: a tubular back frame of rectangular form; a pair of tubular side frames also of rectangular form pivotally connected to said back frame; a vertical leg member continuing from one margin of each side frame to overhang a side of a bed; extension members for said leg members; and securing devices pivotally attached to said extension members constructed and arranged to be secured to the side rail of said bed.

11. A device for installation on a bed to support a patient in a seated position, involving: a tubular back frame of rectangular form; a pair of tubular side frames also of rectangular form pivotally connected to said back frame; vertical leg members projecting from said side frames; means for securing said vertical legs to the side rail

of a bed frame to dispose said frames vertically upon a bed with said back frame upright between said side frames; and a tension strap connected to the lower bar of said back frame for attachment to the opposite side of said bed from legs.
